UNITED STATES PATENT OFFICE

ALEXANDER MACBETH, OF PROVIDENCE, RHODE ISLAND

ASH AND FIRE PROOF CIGAR AND CIGARETTE HOLDER

Application filed May 13, 1931. Serial No. 536,986.

This invention relates to ash and fire proof cigar and cigarette holders and the primary object thereof is to provide a holder of this type which is of improved construction and which embodies novel means for enabling the holder to be easily and quickly attached to and removed from the cigar or cigarette.

The invention further aims to simplify and economize in the construction of the holder so as to enable same to be marketed at a low figure.

The invention has further and other objects which will be later set forth and manifested in the course of the following description.

15 In the drawings:—

Figure 1 is a top plan view of the invention;

Figure 2 is a section on line 2—2 of Figure 1;

20 Figure 3 is a section on line 3—3 of Figure 1;

Figure 4 is a front end elevation.

In proceeding in accordance with the present invention a cylindrical body 1 is provided 25 which is preferably of somewhat tapered formation and which is formed of any suitable fire proof foraminous or mesh material, such as fine screen wire. The outer end of the body has a metal ring 2 applied thereto 30 which latter has an inturned flange 3, to which is secured a similar foraminous or mesh disk 4. The ring 2 is provided with opposed projections 5 that have teats 6 struck inwardly therefrom and which engage in the body 1 so 35 as to secure the end member in position without the use of solder or other extraneous fastening means. The inner end of the body is engaged over a preferably fiber sleeve 7 and is clamped thereto by a fiber ring 8 secured 40 in position by one or more pins 9. In order to strengthen and reinforce the inner end of the body a second fiber ring 10 is engaged over the sleeve 7 and abuts the ring 8 45 and is secured to the sleeve by one or more pins 11. As shown particularly in Figures 2 and 3 the sleeve 7 is formed with a substantially semi-circular slot 12 in which a jaw or clamping member 13 is movable, the member 50 13 having a finger engaging end 14 which

projects beyond the sleeve and is pivoted to the latter by means of a pin 15.

The clamping member or jaw 13 is formed so as to frictionally fit in its slot and engage against the ring 10 so as to somewhat cam 55 thereagainst as shown in Figure 1.

In operation, the cigar after being lighted is placed within the body 1 until its lighted end is adjacent to the end member 4, whereupon the member 13 is moved inwardly so as 60 to clamp the cigar in position, thus maintaining the holder on the end of the cigar. It will thus be apparent that ashes or the like will be held by and within the body 1 and that even though the cigar be placed in contact with any ignitable material or the like, same is prevented from having contact therewith. It will also be apparent that the holder can be made in various sizes, thus for example, in the instance of some cigars or cigarettes the holder will be made of a size smaller than that in the instance of large or average size cigars.

Having thus described my invention what I claim as new and desire to secure by Letters Patent is:

A cigar or cigarette holder composed of a foraminous cylindrical body, a ring disposed over the front end of the body and having an inwardly extending flange, a foraminous 80 disk engaged with the inner face of the flange, said ring having inwardly extending projections with teats struck inwardly therefrom to engage in the body, a sleeve projecting within the rear end of the body, a ring engaged over the body and secured to the sleeve for clamping the body to the sleeve, said body having a substantially semi-circular slot, a second ring abutting the last named ring, and a curved clamping member pivoted in the 85 slot and having camming engagement with the second ring to frictionally hold the member in position against a cigar or cigarette.

In testimony whereof I have signed my name to this specification.

ALEXANDER MACBETH.
